UNITED STATES PATENT OFFICE.

ALFRED W. BENDLIN, OF MILWAUKEE, WISCONSIN.

ASH RECEIVER.

Application filed April 18, 1922. Serial No. 554,862.

To all whom it may concern:

Be it known that I, ALFRED W. BENDLIN, a citizen of the United States, and resident of Milwaukee, in the county of Milwaukee and State of Wisconsin, have invented certain new and useful Improvements in Ash Receivers; and I do hereby declare that the following is a full, clear, and exact description thereof.

10 My invention refers to ash receivers, and it has for its primary object to provide a simple, economical and effective means for firmly attaching an ash receiver to any fixture, such as a table, chair arm or the like.

15 The specific object of my invention is to provide a yieldable attaching means, whereby the ash receiver can be firmly and detachably adjusted to fixtures varying in proportions, the attachment means or grip being 20 yieldably associated with the receiver.

Another object is to provide a spring for permitting yieldably gripping means with an adjusting mechanism, whereby the tension of the spring may be varied, depending upon the thickness of the fixture to which the receiver is attached.

With the above and other minor objects in view, the invention consists in certain peculiarities of construction and combination 30 of parts as are hereinafter described in connection with the drawing and subsequently claimed.

In the drawing,—

35 Figure 1 represents a plan view of an ash receiver embodying the features of my invention, and

Figure 2, a longitudinal section of the same, the section being indicated by line 2—2 of Figure 1.

40 Referring by characters to the drawing, 1 represents an ash receiver of any desired shape and size, having a slip cover 2, which cover is conical in shape with an ash discharge opening 2' therein. The cover may 45 also be provided with one or more receiving shells 3 for supporting a cigarette or cigar. The receiver 1 is also provided with a pocket 4 for the reception of matches.

Secured in any suitable manner to the 50 wall of the receiver, is a vertically disposed tube 5, opened at its upper end and having a closed bottom 5'. The outer face or wall of the tube is slotted from the bottom 5' to a point near the fulcrumed mouth of the 55 tube, and the material is folded outwardly to form guide beads 6—6 for the reception

of a slidable back-bone 7. The back-bone is grooved to conform to the beads 6, whereby relative movement between the back-bone and receiver 1 is permitted in a longitudinal 60 direction, while lateral play is thus avoided. Near its upper end the back-bone 7 is provided with a slot 8, thru which extends a threaded shank 9 of an adjustable stem 9', which stem is formed at its base to the flange 9" and abuts the outer face of the back-bone.

The inner threaded end of the shank 9 is in threaded union with a head 10, between which head and tube bottom 5' there is interposed a coil spring 11. The head and stem when adjusted in the slot 8 are firmly locked.

When it is desired to attach the receiver to a table top or to the fixture A, the downward pressure upon the stem with relation to the receiver 1, will cause the back-bone to be distended in opposition to the coil spring. This action causes a gripping jaw 7', that constitutes part of the back-bone, to spread 75 with relation to the bottom of the receiver, whereby the device, as a whole, can be conveniently slipped over the edge of the table top, as shown in Figure 2. Upon manual release of the back-bone, the spring will exert its pressure to cause the bottom 1' of the receiver to frictionally engage the top of the table A and the jaw 7' will exert pressure upon the bottom of said table, whereby this frictional grip will firmly hold the 85 ash receiver in position.

Obviously either the gripping jaw 7', as well as the bottom of the receiver, may be provided with a suitable felt lining to prevent abrasion of highly polished furniture. 95

While I have shown and described one simple method of manufacturing my portable ash receiver, it is understood that I may vary the structural features of it within the scope of the claims.

I claim:

1. A portable ash tray comprising a closed bottom receiver, having a tubular extension projecting therefrom, provided with a longitudinal slot, a channeled back-bone 105 reciprocably mounted in the slot, the back-bone being provided with an inwardly offset gripping jaw associated with the bottom of the receiver, said back-bone having a slot therein near its upper end, an adjustable 110 stem extending thru the slot, a head carried by the stem adapted to have sliding move-

ment in the tube, and a coil spring mounted in the tube and interposed between the head and bottom of said tube.

2. A portable ash tray comprising a closed bottom receiver, having a tubular extension provided with a longitudinal slot, a back-bone slidably mounted in the tube slot, having a gripping jaw extending therefrom and associated with the bottom of the re-

ceiver, and a coil spring mounted in the tube and exerting pressure in one direction upon the back-bone.

In testimony that I claim the foregoing I have hereunto set my hand at Milwaukee, in the county of Milwaukee and State of Wisconsin.

ALFRED W. BENDLIN.
